UNITED STATES PATENT OFFICE.

DANIEL F. KAY, JR., OF CHICAGO, ILLINOIS.

CLOTHES-PIN.

No. 866,141.

Specification of Letters Patent.

Patented Sept. 17, 1907.

Application filed July 31, 1906. Serial No. 328,580.

To all whom it may concern:

Be it known that I, DANIEL F. KAY, Jr., a citizen of the United States, residing at Chicago, in the county of Cook, State of Illinois, have invented certain new and useful Improvements in Clothes-Pins; and I do hereby declare the following to be a full, clear, and exact description of the invention, such as will enable others skilled in the art to which it appertains to make and use the same.

10 This invention has relation to clothes-pins formed from a length or lengths of wire that will resist corrosion.

The invention comprises a clothes-pin formed from wire and having a head from which depends an elongated loop within a loop of the same form but larger than the inner loop.

15 The annexed drawing, forming a part of this specification, clearly portrays an embodiment of the invention, which will first be described as to its construction and mode of operation and then be pointed out in the subjoined claims.

Of the said drawings, the figure is a front view of a form of means embodying the invention, showing it in place on a clothes line.

20 The device shown in the drawing as embodying the invention consists of a clothes-pin manufactured from wire by bending a portion of a length of wire into an elongated loop 8 with the end and a part above said loop extending from the upper end of the loop in parallel position (not shown) for a short distance to form a neck 11; then bending the length of wire into a small ring for the construction of the inner ring of the head 10; then bending the said length of wire down parallel with the neck-forming portions of the wire before described, and then forming a portion of the wire into an elongated loop 9, larger and longer than the loop 8, and encompassing the same, when the further length of the wire is twisted or wound into close coils or helices about the parallel wires in the neck portion 11 to complete the same, after which said wire is formed into a ring, larger than the first ring to complete the head 10, and the end (not shown) tucked into the top of the neck wires and the base of the head rings bent back and

pressed thereover. Of course the process just described need not necessarily be followed exactly, as any other mode of procedure resulting in substantially the same product would answer as well. Again it is obvious that two lengths of wire might be employed covering the ends of both in the neck 11, and the latter feature might be longer than that represented in the drawings. Under this construction, by taking hold of the head of the pin with the thumb and fore-finger of the hand, the middle loop 8 may be readily pressed outward or laterally in either direction by the middle finger of the hand and with the outer loop resting against the line 12, the said pin can be adjusted astride the clothes on the line, and when the loops are released they will, by their resiliency property, grasp the object between them and hold it securely. The fact that the loops are made to grasp the clothes on the line on opposite sides thereof and are not crowded down or wedged on the clothes, as is the case with the common clothes-pin, is a reason why the present improvement does not, nor is it liable to, injure the fabric by drawing it out of shape, or possibly tearing it.

25 The invention holds the clothes on the line with such security as to make it desirable for use in hanging up heavy articles, such as blankets, carpets, rugs, and similar articles.

The fact that the central or inner loop of the clothes-pin may be bent laterally in either direction, and in practice this will be done, since both sides are alike in appearance and function, the resiliency of the loops are not liable to become impaired by use and hence the invention is contrived to last for years.

30 What is claimed as the invention, is:

A clothes-pin formed from wire and comprising rings forming a head, a narrow neck below the head, and an inner and an outer elongated and closed loop connected with and depending from the head, both loops being of substantially the same form but differing in size, as and for the purpose set forth.

In testimony whereof, I affix my signature, in presence of two witnesses.

DANIEL F. KAY, Jr.
